UNITED STATES PATENT OFFICE.

LEMUER FREDERIC HOWARD, OF EDGEWOOD PARK, PENNSYLVANIA, ASSIGNOR TO THE UNION SWITCH AND SIGNAL COMPANY, OF SWISSVALE, PENNSYLVANIA, A CORPORATION OF PENNSYLVANIA.

CIRCUIT-CONTROLLER.

No. 877,427.

Specification of Letters Patent.

Patented Jan. 21, 1908.

Application filed August 3, 1906. Serial No. 328,998.

To all whom it may concern:

Be it known that I, LEMUEL FREDERIC HOWARD, a citizen of the United States, residing at Edgewood Park, Allegheny county, 5 State of Pennsylvania, have invented certain new and useful Improvements in Circuit-Controllers, of which the following is a specification.

My invention relates to circuit controllers.

10 My invention particularly relates to circuit controllers used in connection with railway appliances such as a switch or signal or with apparatus for operating railway appliances, as for example, power operated switch 15 and lock movements.

I will describe a circuit controller and a modification thereof each embodying my invention and then point out the novel features thereof in claims.

20 In the accompanying drawings, Figure 1 is a view partly in elevation and partly in vertical longitudinal section of a circuit controller embodying my invention. Fig. 2 is a top plan view thereof. Fig. 3 is a view 25 similar to Fig. 1 but showing some of the parts in a different position. Fig. 4 is a view similar to Figs. 1 and 3, but showing a modification embodying my invention.

Similar letters of reference designate 30 responding parts in all of the figures.

A, A¹ designate two compartments which may be integral or not, as desired, and which are fixed to a support by suitable means, as for example, by bolts B. Each compartment is provided with a top a, which is hinged to a plate a¹, forming a cover for a part of the circuit controller to be hereinafter described. The plate a¹ is removably secured by bolts a² to the walls of the compartments 35 40 A, A¹, and the plate a¹ is provided with downwardly extending portions a³, a⁴, provided with openings. A felt or other suitable packing a⁵ is provided between the adjacent faces of the plates a³, a⁴ and the walls of the compartments. 45

Each compartment contains one or more contact springs c, c¹, etc., which are suitably secured to a plate p by binding posts d, d¹. The conductors with which the contact 50 springs are connected are led into the compartments through openings d⁵ provided in walls of the compartments. The plate p is shown as being provided with ribs p¹, the

contact springs being arranged between the ribs, and the plate p carries pieces of insulation i which serves to insulate the contact springs c, c¹, etc., from the plate p. A sheet of insulation i¹ is provided in the bottom of the compartment as shown, upon which the plate p rests, and serves to insulate the contact spring and plate from the compartment. The contact springs c, c¹, etc., and plate may be removed from a compartment for adjustment, cleaning, etc., it being removably secured therein by a pin p² carrying insulation i³ and extending through the side walls of the compartment and through the ribs p¹.

D, D¹, etc., designate movable contact pieces, one such contact piece being preferably provided for each pair of contact springs c, c¹; c², c³, etc. The number of contact springs c, c¹, etc., and contact pieces D, D¹, may vary according to the number of circuits to be controlled. Each contact 75 piece is carried by and suitably insulated from a reciprocating rod E. As shown in the drawings, the movable contacts D, D¹, etc., are arranged in pairs and each pair is removably secured to a cross piece E¹, which 80 in turn is removably connected with the reciprocating rod E. The rod extends through the openings in the portions a³, a⁴, the openings being made weather-tight.

The rod E is reciprocated through a 85 toothed part G, here shown as being a two-toothed pinion and g, g¹, being two teeth. The pinion G is mounted on a pin g² and is provided with an extension g³ carrying a roller g⁴ which fits in a recess e provided in the rod E. The pinion G is rocked on or with the pin g² to give reverse reciprocations to the rod E by a reciprocating part H, which is suitably connected either with a railway part or appliance or with a movable part of an apparatus for moving a railway part or appliance. The part H, as shown, is provided with two openings h, h¹, and adjacent each opening is a stud or projection h². In one direction of movement of the part H, a 100 projection h² causes the tooth g to enter the opening h and thus rock the part G in one direction to reciprocate the rod E, and in the reverse direction of movement of the part H a projection h² causes the tooth g¹ to enter 105 the opening h¹ and thus rock the pinion G in

a reverse direction to reciprocate the rod E in a reverse direction. These movements of the pinion G only occur at the extremes of the movement of the part H, and therefore, 5 a part D is made to engage its pair of contact springs only at an extreme movement of the part H. (See Fig. 3.) When the part H is moved in the other or reverse direction after a full movement (see Fig. 3), 10 the pinion G is rocked to what may be termed a neutral position (see Fig. 1) in which position all the contacts D, D¹, etc. are out of engagement with their pairs of contacts, and the part G is held or locked in 15 this position. It will thus be seen that a circuit is only made at the extreme movement of the reciprocation part, and that the circuits so established are broken immediately that the reciprocating part is moved 20 in a reverse direction, and that all circuits are held or locked open when the reciprocating part is in any position other than its extreme positions.

Instead of a reciprocating rod E, a drum 25 M carrying a contact piece m may be substituted. The contact piece m is suitably secured in the drum M in insulation m¹, and in this form of the invention the contact springs c, c¹, etc., are carried through the 30 openings in the portions a³, a⁴. Insulation i¹ in this form of the invention is substituted for the felt packing a⁵. The operation of this form of the invention is the same as that described in connection with Figs. 1, 2 and 3. 35 It will be seen, therefore, that a circuit controller embodying my invention comprises means for locking the movable contact or contacts at some predetermined position, the closing of one or more circuits at 40 the extremes of the travel of a reciprocating part, the reversal of the operations last performed when the motion of the reciprocating part is reversed, and the locking of all circuits in an open position when the reciprocating part is in a position intermediate its extreme positions.

Having thus described my invention, what I claim as new is:—

1. In a circuit controller, the combination with a plurality of contact springs, a movable contact piece adapted to be engaged and disengaged with said contact springs, a two-toothed pinion connected with said contact piece, and a reversely reciprocating part adapted to alternately engage said teeth at 55 the extremes of its movement and to hold said pinion in a neutral position when not in an extreme position.

2. In a circuit controller, the combination with a plurality of oppositely arranged contact springs, a movable contact piece adapted to be alternately engaged with and disengaged from said contact springs, a toothed pinion connected with said movable contact, and a reversely reciprocating part for operating said toothed pinion, said reciprocating part only operating the toothed pinion at the beginning and extremes of its movements and holding the toothed pinion against movements at any point intermediate the 70 extremes of the movements of the reciprocating part.

3. In a circuit controller, the combination with several pairs of contact springs oppositely arranged, a contact piece for each 75 pair of springs, a two-toothed pinion connected with said contact pieces, and a reversely reciprocating part for operating said toothed pinion at the extremes of its movement to have the contact pieces engage alternately the pairs of contact springs, and to hold the contact pieces disengaged when in any position other than an extreme position.

In testimony whereof I have signed my 85 name to this specification in the presence of two subscribed witnesses.

LEMUER FREDERIC HOWARD.
